METHOD FOR PRODUCING MULTIPLE
ELECTRON DISCHARGE DEVICES

Siegmund Loewe, Berlin, Germany

Application June 12, 1930, Serial No. 460,673
In Germany June 7, 1929

3 Claims. (Cl. 250—27.5)

The invention relates to high emission tubes to be used as amplifying, as rectifying and as transmitting valves. Such high emission valves are, for instance, manufactured at present by the metal vapour process. For this purpose a light metal, usually barium, is atomized in the vacuum and deposited on the cathode surface which, if necessary, has been prepared beforehand. In the case of simple tubes this method entails no difficulty. The anode is used as a carrier for the substance to be evaporated. When this anode is sufficiently heated, the barium will be caused to evaporate. The barium is produced either from barium acetate or from a reaction compound which may consist, for instance, of barium oxide and silicon.

The method will, however, be unsatisfactory if in a common vacuum more than one cathode system is to be coated. The object may, for instance be to produce by the vapour process the filaments of a double tube with two equal amplifier systems, i. e. each consisting of cathode, grid and anode. In this connection I have found that, in order that the tube may be successfully manufactured, it is essential that the systems should be of identical construction, so that the evaporation of the barium in both systems takes place at the same time. If such is not the case, i. e. if the barium in one system evaporates before evaporating in the other one, the quantities of barium precipitated first in the hotter system will be affected by the inevitable discharge of gas preceding the evaporation of the barium in the other system. This results in an unequal deposition of barium on the two systems.

The problem of producing multiple tubes by the evaporation process may, according to the invention, be solved by the various anodes arranged in the tube being made of such dimensions that under the influence of a common eddy current field, effecting the glowing of the anodes, the temperature of the anode systems rises evenly in such a manner that the barium evaporation in both systems takes place at the same time. In carrying out these operations I have found that it is sufficient for the requirements in practice if the cross-sections of the two anodal systems are made equal in the direction of the eddy current field. Physically it is, of course, only necessary for the heat quantities generated in the two anodal systems and for their radiating ratios to be selected so that the rise of temperature in the two anodes takes place at the same time with the same strength in order that the temperature zone of 1000° necessary for the evaporation may

be reached simultaneously in the two anodal systems.

The solution of the problem as above described, i. e. a suitable choice of the heating and radiating conditions of the two anodal systems, however, means a considerable restriction in respect of dimensioning the two amplifier systems. The multiple tube may, for instance, consist of a powerful terminal (end stage) system and a primary stage which is to act as voltage amplifier. The multiple tubes may contain coupling elements for connecting the systems; but my invention is not limited to such kinds of multiple tubes. The terminal stage is in practice appropriately adjusted to a medium emission of 50 milliamperes, while in the other system the emission of the filament is of the order of only one tenth milliampere. In this connection great practical difficulties would arise if both anodes were to be dimensioned according to the above principle. The anode of the voltage stage more particularly would have to be made unnecessarily large.

Therefore, according to my invention, the substances to be evaporated are arranged in such a way that by heating a single system the coating substances for all the systems are vaporized.

My invention will be best understood with reference to the accompanying drawing in which

Fig. 1 shows a double valve, Figures 2 and 3 a triple valve according to my invention.

A pocket in which the reaction for producing barium may take place (Goldschmidt's reaction), is shown on a larger scale in Fig. 4. This pocket of Fig. 4 corresponds to the pockets 5 and 9 of Figures 1 and 3 and to the pockets 5, 9 and 10 of Fig. 2.

In Fig. 1 1 is the cross-section through the glass bulb of a two stage (double) amplifier tube. 2 is the cross-section through the oval-cylindrical anode (plate) of the terminal power stage. 3 indicates by dashes the grid (controlling electrode), 4 the cathode (filament). At 5 a pocket is folded in the anode which pocket, as indicated by hatching, contains the barium reaction compound. Upon the glowing of the anode 2 the barium is liberated, evaporates into the inner anodal space and there precipitates on the filament 4.

The voltage amplifier system consists, for instance, of the anode 6, the grid 7 and the cathode 8. In order to form this cathode 8 also by the metal vapour process, a further pocket 9 is, according to the invention, provided at the anode 2, which pocket, however, while being also filled with the reaction compound, opens up to the out-

side in order to allow the discharging barium metal vapour to precipitate upon cathode 8. The action is not affected if the anode 6 has a higher or lower temperature than anode 2, as it may 5 easily be arranged that at the points where the pockets 5 and 9 are situated the evaporation temperature of barium is reached at the same time. In order to illustrate the process, I have indicated by arrows starting from the two pockets the 10 direction into which the vapour of the barium will go.

At the same time the invention shows a further advance. It is known that cathodes produced by the metal evaporation process sometimes lose in their efficiency. This loss, however, does not occur, if a residue of the vaporizable substance has remained in the cathode and if the anode either under operating conditions or by occasional overloading is subjected to such an 20 increase of temperature that a continuous, though only weak evaporation of the stored barium takes place. It is obvious even if a residue of barium had remained in the anode 6 of the voltage stage, that then owing to the extremely small load of 25 such anode no increase of temperature of the same and therefore no further evaporation would take place. If, however, the metal vapour source for the voltage amplification stage is arranged directly at the power anode 2, upon the overloading 30 of such anode or upon strong operative loading of the same a permanent additional evaporation of the barium will take place by which the voltage stage which remains in itself cold and unloaded will also profit.

35 In Fig. 2 a small modification is shown where more than one primary or initial stage is produced in the same manner. The designations have the same meaning as in Fig. 1, there being, however, a pocket 10 in addition to pocket 9 and a 40 further system 11, 12, 13 in addition to the system 6, 7, 8, the additional system being treated in the same manner as described above.

Fig. 3 shows a somewhat different form of construction in which the barium vapour developed 45 in the pocket 9 feeds not only a single initial stage consisting of the anode system 6, 7, 8, but in the same direction a further initial stage consisting of the system 14, 15, 16.

Naturally the invention may be put into practice in many forms of embodiments. Thus, for 50 instance, the vapour may be passed axially in lengthwise direction through cylindrical systems. Likewise the barium source may be taken for a large number of different systems from a single 55 heatable metal mass which need not necessarily be an anode or generally an electrode of the amplifier systems.

Generally speaking the second way of solving the problem of my invention consists in coating 60 several cathodes belonging to different discharging systems with a highly emissive layer from a common support carrying the barium substance which support has been heated.

65 For electrical reasons it may be necessary to arrange static screens between the anode of the terminal stage 2 and the further amplifier sys-

tems. This may, for instance, be done as indicated on Fig. 1 by a metal sieve 17 being provided between the anode 2 and the system 6, 7, 8. This sieve is connected with any point of constant potential, e. g. the negative end of the heating filament. The barium vapour may pass the sieve without difficulty. Electrically, however, it represents a sufficient screen. Similar grid screens 17 are arranged in Figure 3 between the systems 2, 3, 4 6, 7, 8 and 14, 15, 16.

What I claim is:

1. A multiple valve comprising several electrode systems, each electrode system consisting of a plate, a grid and a cathode coated with a highly emissive barium layer, one of the anodes of said electrode systems being provided with pockets for containing the reaction compounds from which the highly emissive barium layers of the cathodes may be produced, the pocket for containing the barium compound for coating the cathode 15 of the system belonging to said anode being opened to the inside of said system, the pocket containing the barium compounds for coating the cathodes of the other electrode systems being opened towards these other electrode systems, said 20 other electrode systems having no anode-portion between its cathode and the pocket for containing the reaction mixture for coating said cathode.

2. A multiple valve comprising several electrode systems, each electrode system consisting of a 30 plate, a grid and a cathode coated with a highly emissive barium layer, one of the anodes of said electrode systems being provided with pockets for containing the reaction compounds from which the highly emissive barium layers of the cathodes 35 may be produced, the pocket for containing the barium compound for coating the cathode of the system belonging to said anode being opened to the inside of said system, the pocket containing the barium compounds for coating the cathodes 40 of the other electrode systems being opened towards these other electrode systems, said other electrode systems having no anode-portion between its cathode and the pocket for containing the reaction mixture for coating said cathode, and 45 a sieve-shaped screen arranged between said pocket and said electrode systems and adapted to be connected to a suitable potential.

3. A multiple valve comprising several electrode systems, each electrode system consisting of a 50 plate, a grid and a cathode coated with a highly emissive earth alkaline metal layer, one of the anodes of said electrode systems being provided with pockets for containing the reaction compounds from which the highly emissive layers of 55 the cathodes may be produced, the pocket for containing the earth alkaline metal compound for coating the cathode of the system belonging to said anode being opened to the inside of said system, the pocket containing the earth alkaline metal compounds for coating the cathodes of the other electrode systems being opened towards these other electrode systems, said other electrode systems having no anode-portion between 60 their cathodes and the pocket containing the reaction mixture for coating said cathodes.

SIEGMUND LOEWE.
